[57] CLAIM

The ornamental design for a toy caparison, as shown
and described.

DESCRIPTION

FIG. 1 is a top perspective view of the toy caparison
showing my new design,
FIG. 2 is a bottom perspective view thereof,
FIG. 3 is a top plan view thereof,
FIG. 4 is a front elevational view thereof,
FIG. 5 is a rear elevational view thereof,
FIG. 6 is a side elevational view thereof, the side oppo-
site being a mirror image; and
FIG. 7 is a bottom plan view thereof.
